US0D1078669S

(12) **United States Design Patent** (10) Patent No.: **US D1,078,669 S**
(45) Date of Patent: ** Jun. 10, 2025

(54) **SEMICONDUCTOR POWER MODULE FOR VEHICLES**

(71) Applicant: **Semikron Danfoss International GmbH**, Nuremberg (DE)

(72) Inventors: **Ingo Bogen**, Nuremberg (DE); **Jürgen Steger**, Hiltpoltstein (DE)

(**) Term: **15 Years**

(21) Appl. No.: **35/518,972**

(22) Filed: **Oct. 18, 2023**

(80) **Hague Agreement Data**

Int. Filing Date: **Oct. 18, 2023**

Int. Reg. No.: **DM/232850**

CLAIM

The ornamental design for a semiconductor power module for vehicles as shown and described.

DESCRIPTION

1.1 : Perspective

1.2 : Top

1.3 : Back

1.4 : Bottom

1.5 : Front

1.6 : Right

1.7 : Left

The broken lines illustrate portions of the claimed semiconductor power module that form no part of the claimed design.
